UNITED STATES PATENT OFFICE.

GEORGE C. JORDAN, OF STAUNTON, VIRGINIA, ASSIGNOR TO THE RAILWAY STATION INDICATOR COMPANY, OF SAME PLACE.

STATION-INDICATOR.

SPECIFICATION forming part of Letters Patent No. 448,856, dated December 30, 1890.

Application filed April 23, 1890. Serial No. 349,128. (No model.)

To all whom it may concern:

Be it known that I, GEORGE C. JORDAN, of Staunton, in the county of Augusta and State of Virginia, have invented certain new and useful Improvements in Station-Indicators; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

This invention relates to certain improvements in station-indicators.

The object of the invention is to provide an improved station or street indicator for cars exceedingly strong and durable in construction, composed of a minimum number of parts, extremely simple in construction and not liable to become injured or require repairs, capable of being actuated by various operating means, and which will occupy a very small space in the car and project out a minimum distance. These objects are accomplished by and this invention consists in certain novel features of construction and in combinations of parts more fully described hereinafter, and particularly pointed out in the claims.

Referring to the accompanying drawings, Figure 1 is a perspective of one corner of the exterior of a car, showing one of the present indicators in position. Figs. 2 and 3 are elevations of the opposite ends of the indicator, respectively, the casing being removed. Fig. 4 is a front view with the casing removed. Fig. 5 is a section in the plane of line $x-x$, Fig. 2. Fig. 6 is a cross-section taken in the plane of line $y-y$, Fig. 4. Figs. 7 and 8 are views illustrating different methods of operating the indicator.

In the drawings, the reference-letter a indicates the main supporting-frame of the indicator, composed of the two upright narrow parallel sides or ends, located a suitable distance apart, and rigidly and suitably connected and braced and secured at their rear sides to a suitable base or case, so that the device can be easily mounted in the car. These ends are intended to be cast integral

and separate, and thereby reduce the cost of manufacture to a minimum. A pair of main horizontal rollers $b b$ are located in said frame, one directly above the other, and are provided with journals mounted in said two ends. The journals of both rollers are extended through one end of the frame and provided with the pinions $c c$, rigid thereon and both meshing with the large gear-wheel d , loosely mounted on a stud projecting from the exterior of said end, so that both of said rollers will rotate together and in the same direction.

At the lower part of the frame, below and in front of the lower main roller b' , a horizontal small guide-roller e is loosely mounted in the frame ends.

A pair of small parallel horizontal guide-rollers $f f'$ are mounted at the top of the frame and in the same horizontal plane, as shown, so that the front roller f will be in the same vertical plane as the lower guide-roller b' . These two rollers $f f'$ are located a short distance apart, and the two frame ends are provided with vertical guide grooves or ways $g g$, located in a vertical plane between said rollers and extending down a distance below the same and closed at their lower ends and open at their upper ends.

h indicates the name-sheet, of suitable flexible material, at its opposite ends secured, respectively, to and wound in opposite directions upon said two main rollers $b b'$, the sheet extending forwardly from the lower edge of the lower main roller b' to and around the under side of the lower front side of the lower front guide-roller e , and then vertically in front of the frame to the front upper guide-roller f and over the top of the same and the roller f' and down to the rear and around the under side of the other main winding-roller b . The bight of the loop in the sheet between the two rollers $f f'$ loosely contains a heavy metal rod or bar i , at its ends loosely confined in said grooves or ways g . This rod holds the sheet constantly taut and stretched tight between rollers f and e . The rod can be easily inserted or removed from the guide-ways, and merely loosely rests in said bight and holds the same taut by gravity. From the foregoing it will be observed that when

the rollers are rotated the sheet will unwind from one main roller and wind upon the other main roller, and the front vertical portion of the sheet will travel up or down. The names 5 of the stations or streets are placed upon this sheet in consecutive order, as usual.

The indicator is inclosed in a suitable case *j*, provided with an opening in its front side (see Fig. 1) in front of the name-sheet, and 10 which is of such size as to permit the names on the sheet to consecutively and separately appear to the persons in the car as the sheet moves either up or down behind the front of the case.

15 A journal of one of the main rollers (preferably upper roller *b*) is extended through the frame end opposite that upon which the before-mentioned gearing is located, and upon this journal a circuit metal disk or wheel *j'* 20 is rigidly secured. This wheel is provided with a series of peripheral recesses *k*, located an equal distant apart completely around the periphery thereof, and with a circular series of horizontal pins or studs *l* projecting laterally from the outer face of the wheel. There 25 are preferably the same number of studs as there are recesses *k*.

A vertically-movable spring-locking bolt *m* 30 is loosely carried by the ears or projections *n* directly above the operating and locking wheel *j*. The bolt is held bearing down on the upper edge of said wheel by a spring *o*, embracing the same, and the lower end of said bolt is adapted to enter any one of said recesses *k*, and thereby rigidly hold the locking-wheel, and hence the winding-rollers, against 35 rotation. This spring-bolt is operated to release the wheel by means of a cross bar or piece *p'*, pivoted at or near its center to said 40 bar and extending laterally beyond the same in opposite directions with its ends normally resting on stop-pins. The ends of the bar are bent or project outwardly. Thus if either 45 end of said bar is raised the bar will rock upwardly and raise the spring-bolt from locked position against the tension of its spring.

A pair of vertical-sliding operating-bars *q* 50 are located in vertical planes on opposite sides of the operating and locking wheel *j* of the winding-rollers. These bars pass loosely through one or more perforated ears 5, as shown, and at their upper ends are each provided with a longitudinal slot 2, through which a headed pin or screw 3 extends into 55 the frame to hold the bars in position and limit their sliding movement. Near the lower end of the frame the said bars are each provided with a lateral inwardly-extending toe 4, and each bar between its toe 4 and an ear 60 5 is surrounded by a heavy expansive coiled spring 6, constantly forcing the bar down to its limit of downward movement. Each sliding bar is provided with a spring-operating finger or pawl 7 at its lower end, pivoted to 65 its bar beneath the guide-slots therein, so that its upper end, provided at its inner edge with shoulder 8, can swing toward or from pins on

the said locking-wheel. From the shoulder 8 the edge of said finger is inclined or beveled upwardly and outwardly, as shown. Each 70 sliding bar below the said locking-wheel is provided with a lateral arm *q'*, provided at its outer end with an upwardly-extending extension or arm 10, rounded at its upper end and located directly beneath the pins projecting from said locking and operating wheel. Each operating-finger 7 is provided with a retractive coil-spring 11, secured thereto above its pivotal point and at its lower end to the arm *q'*, so as to hold the upper or shouldered ends of the 80 two fingers against the pins on said locking and holding wheel.

A bell 12 or other suitable alarm is secured on a cross-bar 16 at the lower end of the frame. This alarm is provided with a vertically-swinging clapper 13, pivoted to a lug extending up from said cross-bar and provided with a heel or shoulder 14 at its outer end and a spring to yieldingly hold the clapper from engagement with the bell. This 90 clapper is operated by a vertically-rocking horizontal lever 15, pivoted near its inner end to an arm extending up from cross-bar 16, and at its outer end provided with a cross-bar 17, held bearing down on the inner ends 95 of the two lateral toes 4 of the sliding bars *q* by a coil-spring 18, secured to the bar 16 and to the outer arm of the lever. At its inner end the lever is provided with a spring-finger 19, having its lower end located over 100 said heel 14 and its opposite end being provided with a retractive coil-spring 20 to yieldingly hold said lower end in its normal position.

Any suitable mechanism can be employed 105 to operate the sliding bars *q*, either automatic or operated by the conductor or other person in the car. In Fig. 7 the bars *q* are provided with downward longitudinally-slotted extensions, and a T-shaped lever 21 is 110 pivoted beneath the car, so that its vertical arm will engage an incline 22 on the track, as ordinarily, and be rocked thereby, and the two opposite horizontal arms of said lever are 115 respectively confined loosely in said slotted extension, so that when said lever is rocked one of the arms will be swung up, thereby throwing up the sliding bar *q* on that side. As said bar moves up, the upper end of its operating-finger is thrown out by reason of 120 the beveled edge engaging one of the pins of the locking-wheel, and as the bar continues up the shoulder of said finger slips upon said pin and the upper end of the sliding bar engages one end of the rocking cross-bar *p'* and 125 raises the same, and thereby lifts the locking-bolt *m* and releases the operating and locking wheel. The vertical arm 10 moves up with its bar across the face of wheel *j* and beside one of the pins thereon and prevents said 130 wheel from moving in either direction when the locking-bolt is raised and before the bar begins its downward movement. If the arm 10 in moving up should happen to come in di-

rect contact with a pin of said wheel, the bevelled or rounded end of the arm will push the pin to one side, thereby slightly rotating the wheel. When the sliding bar has reached its limit of upward movement, (see right-hand bar, Fig. 2,) the spring 6 throws it down, thereby allowing the spring-bolt to drop upon the edge of the wheel 3, and drawing around said wheel through the medium of the operating-finger and said pin the distance between two pins and recesses *k*, and hence operating the winding-wheels to move the sheet a sufficient distance to display the name of the next succeeding street or station behind the opening in the case, and when moved this distance the bolt *m* will snap into a recess *k* and lock the parts. Each pin *l* is preferably located opposite a recess *k*, and the recesses are located such a distance apart that when the wheel is rotated the distance from one recess to another the name-sheet will travel a distance sufficient to withdraw one and display the next succeeding name. The holding and operating wheel and the name-sheet are operated in opposite directions by the two sliding bars and their operating-fingers, respectively, so that when the car is proceeding in one direction one of said bars and its finger operate the name-sheet, and when the car is proceeding in the opposite direction the other bar and its finger operate the name-sheet in the opposite direction. When either one of said sliding bars is thrown up, its toe 4 engages one end of cross-bar 17, and thereby lifts the outer end of lever 15 against tension of spring 18 and throws down the inner end of said lever, so that the spring-finger 19 will bear down the heel of the bell-clapper and raise the clapper, and will then slip from said end and allow the spring of the clapper to throw against the bell and sound the same. When the lever 15 resumes its normal position, the finger 19, by reason of its spring and pivotal mounting, slips past the heel of the clapper and assumes its normal position. When the car containing the indicator travels back and forth over the same route, of course the name-sheet is moved back and forth, and by the two operating-bars, respectively, when the vehicle is moving in opposite directions; but when the car is not to proceed back over the same route the name-sheet can be moved back in readiness to begin again on the same route by the small hand-crank *w*, projecting through one side of the case and attached (removably or permanently) to the journal at either end of one of the winding-rollers.

The locking-bolt *m* can be provided with a knob or arm *u*, (see Fig. 1,) projecting through a slot in the case, so that the operating and locking wheel can be released when it is desired to rotate the winding-rollers by means of crank *w*.

Various means, as before stated, can be employed to operate the sliding operating-bars, such as cords working over pulleys and connected with said bars and adapted to be

operated by hand; or devices such as shown in Figs. 4 and 8 can be employed.

In Fig. 4 each sliding operating-bar is extended down beneath the bottom of the car and pivoted to one end of a horizontal vertically-rocking lever 24, to the opposite end of which a vertical push-rod 25, extending up through the bottom of the car, is pivoted and adapted to be operated by down-pressure of the foot on said rod. In Fig. 8 the operation is substantially the same, the push-rod and extension of the sliding operating-bar being pivoted to crank-arms extending from opposite ends of a rock-shaft 26, mounted beneath the car-floor.

This indicator is exceedingly simple in construction and sure and reliable in operation and projects out a minimum distance from the wall of the car, being flat and occupying a small space.

It is evident that various changes might be made in the form and construction of the various parts described without departing from the spirit and scope of my invention. Hence I do not wish to confine myself to the precise construction herein set forth; but

What I claim is—

1. In an indicator, the combination of a supporting-frame, winding-rollers mounted therein, a pair of horizontal guide-rollers a distance apart and in substantially the same horizontal plane, the name-sheet operated by said winding-rollers and passing over said guide-rollers, and a metal rod loosely resting on the portion of the sheet between said guide-rollers and loosely confined at its ends in vertical slots and thereby holding the sheet stretched taut, substantially as described. 105

2. In combination, the frame, winding-rollers mounted therein, operating mechanism therefor, a guide-roller in the lower front portion of the frame, a pair of guide-rollers in the upper part of the frame, the name-sheet secured to and wound on said winding-rollers and passing over said guide-rollers and stretched from the lower front guide-roller to said upper rollers, vertical ways at the inner sides of the frame ends between 110 said two guide-rollers, and a heavy rod resting on the portion of the sheet between said two rollers and loosely confined in said ways at its ends, substantially as described. 115

3. In combination, the name-sheet, operating-rollers for and carrying the same, an operating and locking wheel for said rollers, a sliding bar to rotate said wheel, and a lock for the wheel separate from said bar and operated by the same to release the wheel when 120 the bar is operated to rotate the wheel, substantially as described.

4. In combination, the name-sheet, operating-rollers for and carrying the same, an operating and holding wheel rigid with one of 130 said rollers, a lock for said wheel normally holding the same, a vertically-sliding bar operated in one direction by a spring and provided with means for operating it in the

other direction, and an operating-finger carried by said bar to rotate said wheel, said bar being arranged to release said lock from the wheel when operated to rotate the wheel, as 5 set forth.

5. The combination, with the moving name-sheet and its operating-rollers, of the operating and holding wheel for said rollers, a spring locking-bolt for said wheel, having a 10 lateral arm, and a vertically-sliding bar provided with an operating-finger to rotate said wheel, said bar being arranged to engage said lateral arm and raise the bolt from the wheel when operated to rotate the wheel, substantially as described. 15

6. The combination, with the name-sheet and operating-rollers therefor, of the wheel rigid with one of said rollers, having a series 20 of pins projecting from its face and a series of recesses in its periphery, a spring-bolt to enter a recess and lock the wheel, and a vertically-sliding bar having a swinging spring-finger to engage said pins and rotate the wheel when the bar is moved in one direction, substantially as described. 25

7. In combination, the frame, a movable name-sheet, operating-rollers therefor, a wheel rigid with one of said rollers and having a series of peripheral recesses and lateral pins 30 from its face, a spring-bolt bearing down on the periphery of said wheel to enter a recess and lock the same, the two vertically-sliding operating-bars on opposite sides of said wheel, provided with springs to hold them down and 35 with pivoted fingers having springs holding

them in contact with said pins, so that said fingers will respectively rotate the wheel in opposite directions, opposite lateral arms from said bolt above the bars for the purpose set forth, and means to operate said bars, as 40 set forth.

8. The combination, with the name-sheet and the operating-rollers therefor, of the operating-wheel rigid with one of said rollers and having the series of lateral pins from its 45 face, the two sliding operating-bars on opposite sides of said wheel, having fingers to engage said pins and rotate the wheel, each bar being provided with an arm to prevent retrograde movement of the wheel when the bar 50 is moving up, substantially as set forth.

9. The combination, with the indicating devices, the supporting-frame, and a sliding bar to operate the indicating devices, having a lateral arm, of a cross-bar in the lower portion of the frame, a gong mounted on the same, having a spring-clapper, and a spring rocking lever mounted on said bar with one end above said lateral arm and its opposite end having a spring-finger to engage and force 55 down said clapper and suddenly release the same to sound the alarm, as set forth.

In testimony that I claim the foregoing as my own I affix my signature in presence of two witnesses.
